FURNACE

George Moyer, Chicago, Ill., assignor to Riley
Stoker Corporation, Worcester, Mass., a corpora-
tion of Massachusetts

Application May 19, 1936, Serial No. 80,570

6 Claims. (Cl. 110—40)

This invention relates to furnaces, and more particularly to furnaces arranged for the combustion of fuel and the generation of steam.

In one well-known type of furnace, the fuel is delivered to a stationary grate by means of a stoking mechanism located at the front of the furnace and arranged to throw the fuel rearwardly. The grate is frequently of the dumping type having a plurality of sections which can be operated independently. In such furnaces considerable manual labor is required in cleaning the fires, and the operation cannot be performed without the admission of large quantities of cold air and a resultant decrease in efficiency. The stoking mechanism is necessarily somewhat complicated and expensive, since it must distribute the fuel over the entire area of the grate surface with reasonable uniformity. Moreover, substantial quantities of fly ash containing combustible matter are deposited in the gas passages of the boiler, and the removal and disposal of this material presents a further problem.

It is accordingly one object of the invention to provide a furnace which can be operated at high efficiencies and with a minimum of attention.

It is a further object of the invention to provide a comparatively simple, inexpensive and reliable apparatus for burning fuel partly in suspension and partly in a fuel bed.

It is a further object of the invention to provide an improved apparatus for removing fly ash from a boiler and burning the combustible matter therein.

It is a further object of the invention to provide a simple and efficient method of burning fuel, particularly fuel in a crushed but not pulverized form.

With these and other objects in view, as will be apparent to those skilled in the art, the invention resides in the combination of parts and the steps of the process set forth in the specification and covered by the claims appended hereto.

Referring to the drawing illustrating one embodiment of the invention, and in which like reference numerals indicate like parts,

The single figure is a longitudinal section through a steam generating furnace.

The embodiment illustrated comprises a steam boiler of a well-known type having an upper rear transverse steam-and-water drum 10, a lower rear transverse water drum 11 therebeneath, and a front transverse water drum 12. The drums 10 and 11 are connected by a bank of upright water tubes 14, the drums 11 and 12 are connected by a bank of upwardly and forwardly sloping

water tubes 15, and the drums 12 and 10 are connected by a bank of upwardly and rearwardly sloping water tubes 16. A transverse steam drum 18 is mounted above the front water drum 12, this steam drum being connected to the steam-and-water drum 10 by a row of steam tubes 19 which support refractory material 20 forming a roof over the boiler. In association with the boiler there is provided a front wall 22, a rear wall 23, and a combustion chamber 24 located beneath the tube bank 15. A baffle 26 extends upwardly and forwardly from the rear water drum 11, and a baffle 27 extends downwardly from the steam-and-water drum 10, these baffles serving to guide and direct the hot gaseous products of combustion as they flow from the chamber 24 into contact with the several tube banks and thence to a gas outlet 28 in the rear of the steam-and-water drum 10.

The combustion chamber 24 is closed at the rear by a bridge wall comprising refractory material 30 supported by a row of upright water tubes 31 which extend downwardly from the rear water drum 11 to a transverse header 32. A row of water tubes 33 extends upwardly from the header 32 along the front surface of the refractory 30 and thence slopes upwardly and forwardly to the front water drum 12. The sloping portions of the tubes 33 are located a substantial distance below the tube bank 15, thus serving as a slag screen for the boiler.

At the bottom of the combustion chamber 24 there is provided a suitable grate to support a fuel bed and move it slowly toward the front wall 22. For this purpose I preferably utilize a grate 35 of the chain or traveling grate type. The rear portion of this grate is located in the rear of the header 32, a slight space preferably being provided between this header and the upper run of the grate. The front portion of the grate extends beneath the front wall 22 and above an ash hopper 36 which is preferably of the closed type. The grate 35 may be operated under either natural or forced draft, and suitable transverse partitions 37 are provided between the upper and lower runs to provide several zones for the control of the combustion air, as is customary. Air is admitted to the respective zones through openings 38 at the sides of the grate.

The fuel bed is maintained by projecting fuel to the rear portion thereof from the front of the furnace. For this purpose the front wall 22 is provided with an opening 40 located a substantial distance above the grate, and a suitable fuel feeder 41 is mounted in front of this open-

ing. The feeder 41 is enclosed by a casing 42 and arranged to be rotated about a horizontal axis at a substantially constant speed by any suitable source of power. Immediately above the 5 feeder 41 and within the casing 42 there is mounted a rotatable feed regulating device 44 shaped to provide pockets 45 in its periphery. This device 44 is arranged to be rotated about a horizontal axis at a comparatively slow speed by any 10 suitable means, which preferably provides for an adjustment of the rate of rotation. The casing 42 is extended upwardly above the feed regulator 44 to provide a fuel hopper 46.

An appreciable quantity of solid material in 15 the form of fine particles will be carried by the draft into the boiler gas passages. This material is known as "fly ash," and it may contain a substantial proportion of combustible matter. In order to collect this fly ash and recover the heat 20 values contained therein, a hopper 48 is provided in the rear of the bridge wall 30. This hopper communicates at the top with the space between the rear water drum 11 and the rear wall 23, so that solid particles which are carried rearwardly over the top of the baffle 26 and enter 25 the downward pass at the rear thereof will fall by gravity into the hopper. This deposit of material is aided by centrifugal force, since the gases make a sharp upward turn around the baffle 30 27 directly above the hopper. The hopper 48 is shaped and arranged to deliver the collected material directly to the portion of the grate 35 in the rear of the header 32. The discharge of this material from the hopper may be controlled by 35 one or more manually actuated gates 49.

In the operation of the invention the hopper is filled with a suitable fuel, such as crushed but unpulverized coal. The rotation of the pocketed feed regulator 44 supplies fuel at a controlled 40 rate to the rapidly rotating feeder 41 which projects the fuel rearwardly through the opening 48. The fine particles of fuel burn in suspension, while the coarse particles fall on the fuel bed immediately in front of the header 32. The 45 upper run of the grate 35 travels slowly toward the front of the furnace, carrying the fuel bed with it, the rear portion of the fuel bed being continuously replenished by the fresh fuel which is delivered by the feeder. Air for combustion enters through the openings 38 and flows upwardly through the grate so that combustion of 50 the fuel occurs, and at the front of the grate nothing but ash remains, this falling into the ash hopper 36. Sufficient excess air may be introduced through the front portion of the grate 55 to consume the fine fuel particles which burn in suspension. Fly ash which is carried upwardly into the boiler gas passes is for the most part deposited in the hopper 48, whence it is discharged on to the rear portion of the grate 35. The movement of the grate carries this fly ash 60 forwardly beneath the header 32 and into the combustion chamber 24, the combustible matter contained in the fly ash being consumed and the heating value thereof recovered.

The bridge wall 30 is well supported and cooled by the water tubes, it being understood that water flows downwardly in the tubes 31 at the rear of the wall and upwardly in the tubes 33 at the front of the wall. The upper portions of the tubes 33 cool the molten ash particles carried by the gases leaving the furnace and prevent these particles from adhering to the boiler tubes 65. The fuel feeding mechanism 41 can be of comparatively simple and inexpensive construc-

tion, since it projects all of the fuel to the rear of the combustion chamber and is not required to distribute fuel uniformly over a large grate area as in prior constructions. No manual labor is necessary for cleaning the fire, since the grate 5 35 automatically deposits the incombustible matter in the ash hopper 36. The furnace can be operated at high capacities and with high efficiency. Since the fuel is merely crushed and not pulverized, the cost of fuel preparation is very 10 low.

Having thus described my invention, what I claim as new and desire to secure by Letters Patent is:

1. The method of burning crushed but unpulverized fuel in a furnace comprising the steps of providing a fuel bed at the bottom of the furnace, projecting a stream of fuel rearwardly over the fuel bed in spaced relation therewith from the front of the furnace to the rear portion of the 20 fuel bed, subjecting the fuel particles to the radiant heat of the fuel bed during their rearward travel, burning the finer fuel particles in suspension before they reach the fuel bed, and moving the fuel bed toward the front of the furnace. 25

2. A furnace comprising walls forming a combustion chamber, the front wall having an opening therein, an endless grate at the bottom of the combustion chamber and having an upper run arranged to travel to the front of the furnace, 30 and a feeding device arranged to project fuel rearwardly over the grate through the opening to the rear portion of the grate.

3. A furnace comprising walls forming a combustion chamber, the front wall having an opening therein, an endless grate at the bottom of the combustion chamber and having an upper run arranged to travel to the front of the furnace, 35 a rotary feeding device mounted adjacent said opening and arranged to project fuel rearwardly 40 therethrough over the grate to the rear portion of the grate, and means to supply fuel to the feeding device at a controlled rate.

4. A steam generating furnace comprising a boiler, walls forming a combustion chamber beneath the boiler, a grate at the bottom of the combustion chamber and extending rearwardly beneath the rear wall of the combustion chamber and slightly spaced therefrom, a feeding device arranged to project fuel rearwardly from the 45 front of the furnace to the grate immediately in front of the rear wall, and means to collect fly ash from the boiler and deposit it on the grate in the rear of the said rear wall, the grate being movable to move the fly ash and fuel slowly toward the front of the furnace.

5. A steam generating furnace comprising a boiler, walls forming a combustion chamber beneath the boiler, a grate at the bottom of the combustion chamber and extending rearwardly 50 beneath the rear wall of the combustion chamber and slightly spaced therefrom, a feeding device arranged to project fuel rearwardly from the front of the furnace to the grate immediately in front of the rear wall, means to direct the gases 55 from the combustion chamber into contact with the boiler in an upward pass and then rearwardly into a downward pass, and means to collect fly ash at the bottom of the downward pass and deposit it on the grate in the rear of the said rear wall, the grate being movable to move the fly ash and fuel slowly toward the front of the furnace.

6. A steam generating furnace comprising a boiler, walls forming a combustion chamber beneath the boiler, an endless grate at the bottom 75

of the combustion chamber and having an upper run which extends rearwardly beneath the rear wall of the combustion chamber and slightly spaced therefrom, the upper run being arranged to travel toward the front of the furnace, a
5 feeding device arranged to project fuel rear-

wardly from the front of the furnace to the grate immediately in front of the rear wall, and means to collect fly ash from the boiler and deposit it on the grate in the rear of the said rear wall.

GEORGE MOYER. 5
